182,902

COMBINATION IRONING BOARD AND STEPSTOOL

James E. Kemph, Woodstock, Ga.

Application December 11, 1957, Serial No. 48,869

Term of patent 14 years

(Cl. D15—8)

Fig. 1

Fig. 2

Fig. 3

Fig.4

Fig.5

Fig.6

Figure 1 is a perspective view showing my new design for a combination ironing board and stepstool;

Figure 2 is a side elevational view;

Figure 3 is a front elevational view;

Figure 4 is a perspective view of the design when not in use as an ironing board;

Figure 5 is a front elevational view whereof; and

Figure 6 is a side elevational view of the same.

I claim:

The ornamental design for a combination ironing board and stepstool, as shown.
